EXHAUST VENT SUDS CONTROL

Thomas R. Smith, Newton, and Paul S. Decatur, Grinnell, Iowa, assignors to The Maytag Company, Newton, Iowa, a corporation of Delaware

Filed Feb. 8, 1961, Ser. No. 87,889

7 Claims. (Cl. 68—20)

The invention relates to a combination clothes washing and drying unit and has reference in particular to new and improved valve structure for controlling the discharge of foam, soapy water and the like from the exhaust vent of the unit.

In certain machines of the washer-drier type, the arrangement of the exhaust vent and the construction of the air flow passage connecting therewith is such that foam is sometimes blown out of the exhaust vent, when the machine is being drained. Also, it is possible for foam to build up and be discharged from the exhaust vent when the machine is full of water, even though the blower is not operating. To prevent this build up of foam and its discharge, together with suds and the like from the exhaust vent, the invention provides a by-pass opening in the partition wall between the back air flow passage and the tumbler chamber and associates a check valve therewith having an opening movement in a direction towards the tumbler chamber.

Accordingly, the main object of the invention is to provide new and improved structure which will retain within the tumbler chamber any foam that may build up during the washing and rinsing operations and which will also prevent back circulation into the air flow passage of soapy water, suds and the like.

Another object of the invention as regards a combination washer and drier as described resides in locating a check valve between the back air flow passage and the tumbler chamber and which will operate in a manner to eliminate the overflow of suds from the exhaust and which will also eliminate the blowing out of foam and suds from the exhaust at the time the machine is being emptied and with the blower still operating.

Another object is to provide a washer-drier unit where in a part or all of the wash and rinse water is delivered to the back air flow chamber which connects with the exhaust vent, and wherein a by-pass opening with check valve is provided, the same having operation to allow the water to flow from the air flow chamber into the tumbler chamber and to prevent back flow into the air flow chamber.

With these and various other objects in view, the invention may consist of certain novel features of construction and operation as will be more fully described and particularly pointed out in the specification, drawings and claims appended thereto.

In the drawings which illustrate an embodiment of the device and wherein like reference characters are used to designate like parts—

FIGURE 1 is a side elevational view of a combination washer-drier unit, with certain walls being broken away to better illustrate the valve structure of the invention;

FIGURE 2 is a vertical sectional view taken substantially along line 2—2 of FIGURE 1;

FIGURE 3 is a fragmentary view of the present check valve on an enlarged scale, the view being taken substantially along line 3—3 of FIGURE 1;

FIGURE 4 is a front elevational view of the check valve shown in FIGURES 1 and 3;

FIGURE 5 is a vertical sectional view taken through the check valve as on line 5—5 of FIGURE 3, and showing structural details of the same; and

FIGURE 6 is a perspective view of the check valve.

Referring to the accompanying drawings which illus-

2

trate an embodiment of the invention, the combination washer-drier unit includes a substantially flat surfaced base member 10, mounted on legs such as 11. Although only one is shown in the drawings, it will be understood that a pair of channel members 12 are welded in spaced relation or otherwise securely fixed to the base 10 to form the two major supports for the tub and rotating clothes drum of the washer-drier unit.

The channel members 12 are substantially triangular in configuration when viewed in elevation as in FIGURE 10 2. The apex of each member supports a pivot pin 14 and which is journalled by means of the tubular bearing sleeve 15. Accordingly the structure provides a pivotal support for the tub brackets 16, the said brackets being 15 welded or fixed in any suitable manner to the tub or casing generally designated by the numeral 18. The pivoting of the tub on the channel members 12 by means of the pivot pins 14 permits the tub to oscillate back and forth in an arcuate movement in response to various 20 forces generated within the tub.

The tub 18 is maintained in an upright position on the pivot pins 14 by the two centering springs 20 connected between the tub 18 and the base 10 by means of the anchor brackets such as 21 fastened to the respective 25 members. Also, means may be provided in the form of a damper pad and damper leaf spring for absorbing and dissipating the energy imparted to the tub. The damper pad and spring are not disclosed, since they are not concerned with the present invention. However, for 30 a better understanding of the same and for a more complete description of a vent type of washer-drier unit, reference is made to the copending application of Arthur D. Sexton, Serial No. 84,159 filed January 23, 1961, and entitled Gas Fired Combination Washer-Drier.

The tub 18 includes a generally cylindrical side wall 22, a pair of spaced rear walls 24 and 25, and a front wall, not shown, at the front end of the tub, and which includes an opening by means of which the clothes are deposited in the rotating clothes drum 26 of the unit.

The tub 18 is enclosed within the substantially rectangular cabinet generally designated by the numeral 27, the front wall of which is likewise provided with an opening in alignment with the opening in the tub and which is provided with the conventional door having a glass window. The rear wall 24 and the front wall are, respectively, connected to the cylindrical side wall 22 by means of an encompassing flanged loop-like member 28. The intermediate rear wall 25 is suitably welded to the cylindrical side wall 22, and it will be understood that the 40 spaced walls 24 and 25 support the tub bearing assembly including a spacer hub 23 located between and fixed to the walls 24 and 25. The spacer hub journals a drive shaft 29, FIGURE 2, which extends rearwardly of the outer rear wall 24 and forwardly beyond the intermediate wall 25. The rear extending portion of the drive shaft 29 has the drive pulley 30 fixed thereto. The endless belt 31 passes around the pulley and by means of an electric motor or other form of power, the pulley 30 and its drive shaft 29, are rotated. The forwardly extending end of said drive shaft has the perforated clothes drum 26 suitably fixed thereto as by 50 means of the perforated end wall 32 of the clothes drum. Accordingly, the drum is adapted to rotate within the tumbler chamber of the tub. In the illustrated embodiment transmission mechanism of the solenoid operated type is provided and which when energized produces rotation of the drum at a speed of approximately 300 revolutions per minute and when de-energized the clothes drum is caused to revolve at a speed of approximately 65 50 revolutions per minute.

The tub 18 is formed to provide a lower recessed portion 34 which forms a sump for the tub, the sump

34 communicates with the drain pump 35, and the sump also includes a perforated tray 36 for preventing foreign particles, passing through the perforated clothes drum 26 and into the tub 18, from entering and damaging the pump 35. The drain pump is driven by the electric motor which rotates the clothes drum 26, and for this purpose the pulley 37 and endless belt 38 are provided.

The sump 34 is positioned between the intermediate wall 25 and the outer front wall of the tub casing. Accordingly the sump receives the washing and condensing fluids discharged into the tub casing 18 and the liquids are drained from the sump by the drain pump 35. It is, of course, necessary to provide a valve, not shown, on the drain pump in order to retain the washing liquids within the tub during the washing and rinsing operations of the combination unit.

In accordance with the invention a drain aperture 40 is provided in wall 25 to enable the washing liquids within the back passage 39 between the rear walls 24 and 25 to flow into the sump 34 for eventual discharge by the drain pump. In connection therewith the invention contemplates the provision of a check valve 41 for normally closing the aperture 40. In FIGURE 1 the valve is shown closed. Its opening movement is in a direction towards the tumbler chamber of the tub 18, the said chamber containing the perforated clothes drum 26. The structure and operation of the check valve will be explained in more detail as the description proceeds.

Mounted on the side wall 42 of the cabinet 27 is a gas burner assembly having a part 43 projecting through an opening 44 in the cylindrical wall 22 of the tub casing 18. The burner, including part 43, extends through the opening 44 and into a combustion chamber 45, having the general configuration of a rectangular box with open ends such as 46 and 47, and top and bottom walls 48 and 50. The open flame of the gas fire from burner 43 is thus contained within the confines of chamber 45.

The path of air flow in the combination washer-drier unit as disclosed, is from atmosphere opening 44 in the tub wall 22, through the combustion chamber 45, through the conduit 52 mounted on the tub 18 and into the perforated clothes drum 26. After traversing the clothes within the drum 26, the air is removed through an opening 53 in the intermediate wall 25, and said air is then forced through the outlet or exhaust passage 54 located in the back passage and formed by duct work including cylindrical wall 22, side walls 24 and 25, and an arcuate top wall 55. From the said exhaust passage the air is discharged through an exhaust and vent opening 56 formed in the rear wall 24.

Water for the washing operation is partly supplied by the flexible hose or conduit 60 which discharges into the cup 61 provided on the cylindrical wall 22 of the tub. The water from hose 60 thus drains into the tumbler chamber of the tub within which is located the perforated clothes drum 26. Some of the wash water may also be supplied by a second flexible hose or conduit 62. The hose 62 discharges into the cup 63 and a length of hose 64 may conduct the water from the cup and discharge the same onto the blades of the impeller 65. A housing for the impeller-type fan 65 is produced by cooperation of the rear walls 24 and 25 with an imperforate scroll-shaped enclosing wall 66 as clearly shown in FIGURE 2. The impeller housing is suitably connected with the duct work forming the passage 54 and which accordingly extends from the scroll-shaped housing 66 to the exhaust vent 56. With the hose 64 discharging water against the rotating impeller blades, the stream is broken up in a manner to produce a flushing spray during the fill portion of the cycle of operations for the purpose of flushing the impeller, housing, and associated duct free of lint.

In operation during a washing process, water is fed

into the tub to the desired level by means of the conduits 60 and 62. The said conduits connect with the main water supply hose 68 having connection with a control valve 70 of the solenoid actuated type. The fluid level within the tub is suitably controlled by means of pressure diaphragm switch mechanisms, not shown, and which is suitably connected to a fill valve solenoid in the usual manner.

It will be understood that the impeller 65 rotates continuously during the washing, rinsing and drying cycles, since the impeller is driven by the same motor that produces rotation of the clothes drum 26. However, during the washing and rinsing cycles, when the water within the tub 18 is above the low point in the exhaust passage 54, it will be seen that a water trap is provided preventing air flow from taking place in the said passage. The water is drained from the drum for a drying cycle, and thus the heated air from the chamber 45 is drawn into the clothes drum 26 through the perforations therein for drying the clothes. The air is then withdrawn by the impeller 65 and forced to flow in the exhaust passage 54 for eventual discharge to the exhaust opening 56.

During a washing and rinsing operation the production of soapy water, suds and the like in the back chamber is controlled by delivering part or all of the incoming wash and rinse water to the said back chamber, and then allowing the water to flow into the tumbler chamber through the drain aperture 40 which, however, is normally closed by the check valve 41. The action of the check valve is to prevent reverse circulation of the suds and soapy water into the back chamber and into the air flow passage which leads to the vent opening. As best shown in FIGURE 5, the check valve generally designated by the numeral 41, is preferably formed of rubber or other suitable resilient material and the same is disposed as shown in FIGURE 1 on the right side of the drain aperture 40 and within the tumbler chamber of the tub. The check valve is suitably secured at its upper end 40 to the top edge of the drain aperture by means of the spaced portions 71, and the valve member depends vertically to thus normally maintain the drain aperture closed due to the natural biasing action of the valve member in this direction. When the water on the left 45 side of the valve reaches a predetermined level, the pressure of the water will be sufficient to force the valve member in a direction towards the right as shown in dotted lines in FIGURE 5. This opening action of the valve is facilitated by the grooves 72 formed therein and 50 disposed horizontally of the member. The grooves tend to weaken the valve for bending in this direction, thus effecting an opening action with considerably less water pressure than would otherwise be the case.

With the check valve 41 opening in a right hand direction, it will be appreciated that the water from the back chamber will be permitted to flow into the tumbler chamber, and that such flow will take place automatically when the water within the back chamber reaches a predetermined level as described. With the check valve closed, 60 any foam that may build up within the tumbler chamber is confined within the chamber and the suds and soapy water from the tumbler chamber are effectively prevented from passing into the exhaust passage 54. Thus the check valve eliminates the possibility of any foam, suds or the like from being blown out of the exhaust vent as the water is being drained from the tub. Also, during operation, the production of such foam and suds within the back chamber is prevented so that here again the possibility of the same being vented from the exhaust opening 70 is substantially eliminated.

The invention is not to be limited to or by details of construction of the particular embodiment thereof illustrated by the drawings, as various other forms of the device will, of course, be apparent to those skilled in the

art without departing from the spirit of the invention or the scope of the claims.

What is claimed is:

1. In laundry apparatus, the combination including a tub casing providing a washing and drying chamber, a clothes receptacle rotatably mounted within said chamber on a non-vertical axis, an air circulating fan communicating with the chamber, an exhaust opening communicating with said tub casing, duct work located exteriorly of the chamber and connecting the pressure side of the fan with the exhaust opening whereby an air flow passage is provided, water supply means having connection with said tub casing so as to deliver water to the air flow passage, a wall of said duct work having an opening therein connecting the air flow passage with the chamber, and a check valve normally closing said opening, said check valve when open admitting water from the air flow passage to the chamber, and said check valve when closed preventing foam, suds and the like such as may develop within the chamber from entering the air flow passage.

2. Laundry apparatus as defined by claim 1, wherein the check valve comprises a member of resilient material and which opens automatically in a direction towards the chamber for admitting water from the air flow passage to the chamber.

3. Laundry apparatus as defined by claim 1, wherein the check valve comprises a member of resilient material, and wherein said check valve opens automatically in a direction towards the chamber for admitting water from the air flow passage to the chamber when the level of water in the air flow passage produces a pressure against the check valve sufficient to overcome its natural biasing action in a closing direction.

4. In laundry apparatus, the combination including a tub casing providing a washing and drying chamber, a clothes receptacle rotatably mounted within said chamber on a non-vertical axis, an air circulating fan communicating with the chamber and operative to withdraw air from the chamber, an exhaust opening communicating with said tub casing, duct work located exteriorly of the chamber and connecting the pressure side of the fan with the exhaust opening whereby an air flow passage is provided, water supply means having connection with said tub casing so as to deliver water to the chamber and to the air flow passage, a wall of said duct work having an opening therein connecting the air flow passage with the chamber, and a check valve normally closing said opening, said check valve having a location on the side of the opening within the chamber whereby the valve opens in a direc-

tion towards the chamber for admitting water from the air flow passage to the chamber, and said check valve when closed preventing foam, suds and the like such as may develop within the chamber from entering the air flow passage.

5. In a machine for washing and drying fabrics during washing and drying operations, a generally cylindrical tub including a cylindrical shell, a front wall and spaced inner and outer rear walls, whereby said tub provides a tumbler chamber between the front wall and the inner rear wall, and provides a back chamber between the said rear walls, a rotatable perforate drum positioned in the tumbler chamber for receiving and tumbling fabrics during the washing and drying operations, an impeller located between the spaced rear walls and communicating with the tumbler chamber through an opening in the inner rear wall, an exhaust conduit connecting with the back chamber through an opening in the outer rear wall, duct work including said spaced rear walls providing an air flow passage connecting the pressure side of the impeller with the exhaust opening, said inner rear wall in the vicinity of the lowest point in the air flow passage having an opening for connecting the air flow passage with the tumbler chamber, and a check valve normally closing said opening, said check valve when open admitting water from the air flow passage to the tumbler chamber, and said check valve when closed preventing foam, suds and the like such as may develop within the tumbler chamber from entering the air flow passage.

6. A machine for washing and drying fabrics as defined by claim 5, wherein the check valve comprises a member of resilient material and which opens automatically towards the tumbler chamber for admitting water from the air flow passage to the chamber.

7. A machine for washing and drying fabrics as defined by claim 5, wherein the check valve comprises a member of resilient material and wherein said check valve opens automatically in a direction towards the tumbler chamber for admitting water from the air flow passage to the chamber when the level of the water in the air flow passage produces a pressure against the check valve sufficient to overcome its natural biasing action in a closing direction.
